UNITED STATES PATENT OFFICE.

WALTER J. SHEPARD, OF BUFFALO, NEW YORK.

ICE-CREAM FREEZER.

SPECIFICATION forming part of Letters Patent No. 448,375, dated March 17, 1891.

Application filed December 15, 1890. Serial No. 374,736. (No model.)

To all whom it may concern:

Be it known that I, WALTER J. SHEPARD, a citizen of the United States, residing at Buffalo, in the county of Erie and State of New York, have invented new and useful Improvements in Ice-Cream Freezers, of which the following is a specification.

This invention relates to that class of ice-cream freezers in which the scraper adjusts itself automatically to the inside of the cream-can. Heretofore this adjustment has been effected by interposing springs between the scraper and the actuating-spindle. It has also been proposed to connect the scraper with the spindle by levers in such manner that the weight of the scraper would cause it to bear against the inside of the can. These devices are objectionable because the numerous parts are difficult to clean and are necessarily cumbersome and liable to get out of order.

The object of my invention is to provide simple mechanism whereby the weight of the scraper is utilized for pressing the latter against the inner side of the cream-can.

In the accompanying drawings, Figure 1 is a sectional elevation of a cream-freezing can provided with my improved scraper. Fig. 2 is a fragmentary elevation showing the reverse side of the scraper and its supports. Fig. 3 is a horizontal section in line $x-x$, Fig. 1, looking downward. Fig. 4 is a similar fragmentary section in line $y-y$, Fig. 1, looking upward. Fig. 5 is an elevation of the upper arm of the scraper. Fig. 6 is a bottom plan view thereof. Fig. 7 is a fragmentary elevation of the bracket supporting the upper arm of the scraper. Fig. 8 is a top plan view thereof.

Like letters of reference refer to like parts in the several figures.

A represents the cream-can, which is immersed in the freezing mixture contained in a wooden tub and provided at its bottom with a stud or journal a , which turns in a socket or step-bearing arranged in the bottom of the tub in the usual manner.

B is the cover of the cream-can, and C is the vertical shaft or spindle on which the dasher c and the scraper D are pivotally supported.

The shaft is supported at its lower end in a

step-bearing d , secured to the bottom of the cream-can and passes with its upper end through an opening in the cover B. The cream-can is revolved and the shaft is held stationary; but, if desired, the can and the shaft may be revolved in opposite directions in any suitable and well-known manner.

g g' represent laterally-extending brackets formed on the shaft and supporting the upper and lower ends of the scraper. These brackets are arranged near the upper and lower ends of the shaft and extend, preferably, in a diametrically-opposite direction from the arms supporting the dasher.

H H' represent arms secured to the upper and lower ends of the scraper and pivoted to the brackets g g' , so that the scraper is enabled to swing on a vertical axis toward and from the inner side of the cream-can. The lower arm H' is provided with a vertical plate h' , by which it is secured to the lower rear side of the wooden scraper, and has an eye or socket by which it turns on a depending pin I , formed on the outer end of the lower bracket g' . The upper arm H is provided with a vertical plate h , by which it is secured to the upper rear side of the wooden scraper, and has an eye or socket by which it turns on an upright pin J , formed on the outer end of the upper bracket g . The scraper swings on these vertical hinge-pins toward and from the inner side of the can.

K represents an incline formed on the lower side of the upper arm H , adjacent to the front side of its eye, and m is a similar incline formed on the upper side of the upper bracket at the base of the pin. These inclines slope outwardly, or toward the can, and cause the scraper to exert a constant pressure against the inside of the can, owing to the tendency of the scraper to gravitate down the inclines and in so doing swing outwardly on its pivots. If the can has been indented so as to present irregularities on its inner side, the scraper upon striking the same will swing forwardly on its pivots and ride upwardly on the incline m , and upon clearing the obstruction will ride down over the incline and swing backwardly on its pivots, thereby automatically adjusting itself to any irregularities which may exist in the interior of the can and in-

suring a removal of the frozen cream before it has unduly accumulated. The upward movement of the scraper is limited by its lower arm striking against the under side of the lower bracket. The backward movement of the scraper is limited by the rear side of the upper arm striking against a projecting nose on the upper bracket M, as represented in Fig. 4. It is obvious that one of the inclines may be omitted by making the contact-surface of the other part comparatively narrow; but I prefer to use both inclines, as they afford a firmer support for the scraper in its movements.

15 I claim as my invention—

1. The combination, with the can, of a scraper, a support to which the scraper is piv-

oted, and an incline which causes the scraper to rise as it swings away from the can and to descend in swinging toward the can, substantially as set forth.

2. The combination, with the can, of a scraper, a support to which the scraper is pivoted, an inclined face or cam formed on said support, and a similar incline formed on the scraper and resting on the incline of the support, substantially as set forth.

Witness my hand this 12th day of December, 1890.

WALTER J. SHEPARD.
